CLAIM

I claim the ornamental design for a tamper evident container closure, as shown and described.

DESCRIPTION

FIG. 1 is a perspective view of a first embodiment of a tamper evident container closure in a closed condition; FIG. 2 is another perspective view thereof in an open condition;

FIG. 3 is a perspective view of a second embodiment of a tamper evident container closure in a closed condition; FIG. 4 is another perspective view thereof in an open condition;

FIG. 5 is a perspective view of a third embodiment of a tamper evident container closure in a closed condition; and, FIG. 6 is another perspective view thereof in an open condition.

In the drawings, the evenly-spaced broken lines show portions of a container closure that form no part of the claimed design; and the dash-dot-dash broken lines represent boundaries of the claimed design and form no part thereof. The shapes shown in solid black color in the drawings represent surface treatment of the claimed design.
